SPARK PLUG

Charles R. Buening, Milwaukee, Wis., assignor to
Globe-Union Inc., Milwaukee, Wis., a corpora-
tion of Delaware

Application July 14, 1939, Serial No. 284,393

13 Claims. (Cl. 123—169)

This invention relates to an improvement in spark plugs of the type wherein the insulator of the central electrode, usually in the form of a body of porcelain or the like, is assembled with and hermetically sealed and secured to the outer metallic bushing or shell which carries or functions as the grounded electrode, and which is threaded into the opening provided therefor in the engine.

10 In structures of this type, it is necessary to effect a hermetic seal between the insulator and the metallic bushing or shell, and for this purpose it has been common practice to employ a gasket located relatively inwardly of the structure. In types of spark plugs where the parts are maintained in assembly by the use of a packing nut or gland, an outer gasket is also employed which serves not so much as a sealing device as a cushioning and locating device. Reliance for the required seal is placed upon the inner gasket.

15 One of the very common faults of most spark plugs is leakage of the inner gasket, the one relied upon to effect the seal. Such leakage permits hot gases to traverse the gasket, resulting in rapid deterioration of the gasket, thereby increasing the leakage and consequently involving loss of compression and power in the engine. In this type of construction as heretofore devised, the plugs may be assembled so that they do not leak originally, but, due to the differential expansion of the various parts, leaks develop as the plugs are heated up in service. To overcome this difficulty, it has been common practice to excessively tighten up the assembly, and this results in the setting up of excessive stresses in the insulator and squeezing or distorting the gasket to such an extent that a two-piece plug cannot later be disassembled.

20 One of the important objects of the present invention is to provide a construction which effects such a gas-tight or hermetic seal at the inner gasket that the plugs do not leak when cold and also do not develop leaks when they are heated. This result is accomplished with a minimum tightening or squeezing force on the inner gasket so that excessive stresses are not set up in the insulator. Furthermore, such stresses as are set up are directed away from the portions of the insulator least adapted to withstand the same.

25 The accomplishment of the objects and advantages so far pointed to is realized principally by cadmium plating the inner or bottom gasket, the one relied upon to effect the hermetic seal of this spark plug assembly. The phenomenon

which underlies the action of such structure is not clearly and fully understood, but it has been found that spark plugs so constituted, even though tending to leak slightly when first assembled, will, if put in an engine and subjected to use for several days, seal up. Another characteristic that may be mentioned is that after plugs of this type have been tightened up and allowed to stand for some time, or operated in an engine, the metal of the gasket apparently flows into the pores of the insulator to such an extent that if the plug were disassembled it would be practically impossible to remove the gasket from the insulator.

30 The invention may be embodied in various types of spark plugs. In the type of spark plug where the insulator is held assembled with the shell by means of a packing nut, the cadmium plated sealing gasket is combined with the outer locating and cushioning gasket in a special manner, in that the outer cushioning or locating gasket is so constituted as to minimize the transmission of any turning movement from the packing nut to the insulator. This action is especially advantageous for the reason that the cadmium plated inner seal gasket not only effects this sealing function but also locks or holds the insulator against turning movement. However, many of the important advantages of the present invention are realized in other types of structure—for example, with the so-called one-piece spark plug construction, that is the type of structure where a packing nut is not employed, but the insulator is held assembled with the metallic shell or bushing by crimping or displacing the metal of the bushing over the upper end of the insulator. In this type of structure the cadmium plated inner gasket exerts this desirable sealing function, relieves the portions of the insulator least adapted to bear the same of excessive stresses, and holds it in place.

35 Approximately the same results may be obtained by tin-plating or lead-plating the inner sealing gasket, but it has been found in actual practice that cadmium-plating is the best.

40 A further object of the invention is to improve, simplify, and compact a structure of this character in such manner as to secure the desired seal while precluding injury, damage, or over-stressing of the component parts employed.

45 A still further object of the invention is to provide a structure having the advantages mentioned, and which is simple and durable in construction, reliable and effective in operation, and

easy and comparatively inexpensive to manufacture.

Other objects and advantages reside in certain novel features of construction, arrangement, and combination of parts, which will be hereinafter more fully described and particularly pointed out in the appended claims, reference being had to the accompanying drawing forming a part of this specification, and in which:

10. Figure 1 is a view partly in vertical, diametric cross section, and partly in side elevation, showing a spark plug constructed in accordance with the present invention.

15. Figure 2 is a fragmentary detail view on an enlarged scale showing the upper gasket of the spark plug, partly in cross section, and partly in elevation.

20. Figure 3 is a view similar to Figure 2, illustrating the structure of the lower gasket as it approximately appears after it has been in use, or compressed.

Figure 4 is a detailed perspective view of the upper gasket;

25. Figure 5 is a detailed perspective view of the lower gasket; and

Figure 6 is a fragmentary view in cross section showing the lower gasket as it is constituted before assembly and compression.

The invention will be illustrated and described 30 as embodied in the type of spark plug which has a metallic shell or bushing, an insulating body surrounding the central electrode, and a packing nut for maintaining these parts but, as indicated, it is of course susceptible of embodiment in the 35 one-piece structure previously described.

Referring to the drawing, the numeral 10 designates the bushing or metallic, shell-like body of the spark plug, which is externally threaded, as at 11, at its lower end to adapt it to be threaded 40 into the opening provided therefor in the cylinder head of the engine (not shown). The insulator, usually in the form of a body of porcelain, and designated at 12, is assembled with the metallic body 10. This insulator, as usual, surrounds the central electrode 13, the electrode 13 projecting beyond the lower end of the insulator and being equipped at its upper end with a thumb-nut or binding nut 13'. The lower end of the central electrode 13 is in cooperative relation 45 to the grounded electrode 14 of the plug, which is carried by the lower end of the metallic body 10.

A sleeve-like packing nut 15 surrounds the portion 16 of the insulator 12, and below its hexagonal head 17 is externally threaded, as at 18, the threads 18 being threadedly engaged, when the parts are assembled, with internal threads 19 provided in the upper end portion of the metallic body.

Internally the metallic body 10 is provided with 50 an upwardly facing, annular shoulder or gasket seat 20. A gasket 21 rests on this seat in the assembly and is engaged by a downwardly facing, annular shoulder or gasket seat 22 formed on the porcelain body of the insulator 12. Above the 55 seats 20 and 22 the porcelain body is provided with an upwardly facing, annular shoulder or gasket seat 23 engaged by a second gasket 24. The lower end of the packing nut 17 is formed with a downwardly facing annular shoulder or 60 gasket seat 25, which engages the top side of the body of the gasket 24. The gasket 24 is formed with an integral neck portion 26, which is accommodated in an internal annular recess 27 in the lower end of the packing nut 17.

75. The present invention proposes to constitute

the gasket 21 of an annealed or soft metal body 28, usually of copper, although it may be of any metal of high heat conductivity, such as silver, save that metal such as silver involves a considerable item of expense. Where the body is constituted of copper, it is coated with a metallic coating or plating 29 of cadmium, nickel, tin, or lead, or the like, applied thereto by electrode deposition, or by dipping.

The body portion and the neck of the upper 10 gasket 24 are constituted of relatively hard metal, usually brass, but which may be steel, copper, aluminum, or some suitable alloy. Its essential characteristic in this type of structure is that it be appropriately hard, and that it be provided 15 with a coating or film 32 of a lubricant, such as wax, paraffin, oil, or other friction-reducing material.

In addition to the foregoing, the seat or shoulder 23 on the porcelain body 12 is smooth or glazed, whereas the seat or shoulder 22 thereof is rough, that is unglazed or bisque.

With a construction of this character, when the parts are assembled, and the packing nut 15 is tightened, the gasket 21, and its cooperating gasket seats, will first operate to hold the insulator 12 against turning, and this action on the part of the element is aided by the capacity present in the upper gasket 24 and its cooperating seat 23 for slippage. The tightening action of the nut is thus transferred largely as a straight axial pressure, or as a pressure parallel to the axis of the insulating body, and the tendency to set up torsion or twisting strains, or strains in the fillets or localized portions of the insulator least liable to withstand them, are all very substantially reduced or minimized. The result is a permanent gas-tight or hermetic seal between the gasket 21 and its seats, and a substantial reduction in strain in all portions of the plug. Since 40 no parts of the spark plug are over-stressed, or subjected to any great concentration of stresses, the plug in use is better able to withstand impacts or mechanical blows or shocks, and also the stresses and strains incident to severe changes in 45 temperature.

The plated inner gasket 21, when pressed between its seats in the assembly provides the most effective hermetic seal, and in so doing it flows upwardly and away from the juncture of the tapered lower portion of the insulator and its relatively thick body. This is important, as it relieves this juncture, a part less adapted to withstand stress of any kind incidental to the seal desired.

The invention possesses its marked utility when embodied in a spark plug of the type illustrated, but many of the advantages may be realized in other designs. For example, in the one-piece mechanically crimped and electrically heated or compressed type of spark plug, or the one-piece mechanically twisted under vertical pressure, all of the desirable characteristics of the gasket 21 and its plating or coating are realized.

While I have shown and described one construction in which the invention may be advantageously embodied, it is to be understood that the construction shown has been selected merely for the purpose of illustration or example, and that various changes in the size, shape, and arrangement of parts may be made without departing from the spirit of the invention or the scope of the subjoined claims.

I claim:

1. A spark plug of the character described 75

comprising a metal shell having an upwardly facing inner gasket seat, an inner gasket engaged with said seat, an insulating body having a downwardly facing gasket seat engaged with said gasket, said insulating body having an upwardly facing outer gasket seat, an outer gasket engaged with said outer gasket seat, a packing nut threadedly connected with said shell and having a downwardly facing seat engaged with said outer gasket, said inner gasket being constituted of relatively soft metal having a coating adapted to have gripping and hermetic sealing engagement with the adjacent gasket seats to hold the insulated body against turning, said outer gasket being constituted of relatively hard metal and having an anti-friction coating designed to permit slippage between the outer gasket and its cooperable gasket seats.

2. A spark plug of the character described comprising a metal shell having an upwardly facing inner gasket seat, an inner gasket engaged with said seat, an insulating body having a downwardly facing gasket seat engaged with said gasket, said insulating body having an upwardly facing outer gasket seat, an outer gasket engaged with said outer gasket seat, a packing nut threadedly connected with said shell and having a downwardly facing seat engaged with said outer gasket, said inner gasket being constituted of soft metal having a coating of cadmium, the downwardly facing inner gasket seat of the insulated body being unglazed whereby the inner gasket when compressed between its seats will hermetically seal thereunto and hold the insulating body against turning, the outer gasket being constituted of a hard metal having a lubricating film thereon, the upwardly facing gasket seat on the insulating body being glazed whereby when the packing nut is tightened the outer gasket may slip relative to its seats to permit the packing nut to compress the inner gasket with straight axial pressure.

3. A spark plug of the character described comprising a metal shell having an inner gasket seat, an inner gasket of soft gripping as well as hermetic sealing material engaged with said seat, an insulating body having an inner gasket seat engaged with said inner gasket and also having an outer gasket seat, a hard outer gasket having lubricated gasket seat-engaging surfaces, and a packing nut threaded to the shell and having a gasket seat engaged with the outer gasket.

4. A spark plug of the character described comprising a metal shell having an inner gasket seat, an inner gasket of soft gripping as well as sealing material engaged with said seat, an insulating body having an inner gasket seat engaged with said inner gasket and also having an outer gasket seat, a hard outer gasket having lubricated gasket seat-engaging surfaces, and means interconnected with the shell and having a gasket seat engageable with the outer gasket to effect compression of both gaskets and cause the inner gasket to hermetically seal with and hold the insulating body against turning movement relative to the shell.

5. A spark plug of the character described and including a metallic shell, an insulating body, an inner non-ferrous metallic gasket having a soft metal coating, and means for maintaining the body and shell assembled and compressing the inner gasket into hermetic sealing engagement with the insulating body and the shell.

6. A spark plug of the character described comprising a metallic shell having an outwardly and outwardly upwardly inclined inner gasket seat, an insulating body having a portion of relatively large diameter and an inner tapered portion, and provided with an inwardly and downwardly inclined shoulder at the juncture of said portions, a non-ferrous metallic gasket having a soft metal plating interposed between said seat and said shoulder, and means for holding the shell and body assembled and for forcing the body inwardly of the shell to compress the gasket between the shoulder and the seat and cause it to flow away from said juncture whereby to effect a hermetic seal between the body and the shell without application of stress to said juncture.

7. A spark plug of the character described comprising a metal shell having an upwardly facing inner gasket seat, an inner gasket engaged with said seat, an insulating body having a downwardly facing gasket seat engaged with said gasket, said insulating body having an upwardly facing outer gasket seat, an outer gasket engaged with said outer gasket seat, a packing nut threadedly connected with said shell and having a downwardly facing seat engaged with said outer gasket, said inner gasket being an annealed soft metal such as copper having a coating or plating of cadmium or the like so as to hermetically seal the parts and hold the insulating body against turning when compressed against its seat, said outer gasket being constituted of a relatively hard metal such as brass having a lubricating coating of wax or the like so as to permit of slippage between itself and its seats whereby when the packing nut is tightened the gaskets can be compressed without setting up twisting strains or excessive stresses in the elements of the plug.

8. A spark plug of the character described and including a metallic shell, an insulating body, an inner non-ferrous metallic gasket having a soft metal plating, and means for maintaining the body and shell assembled and compressing the inner gasket into hermetic sealing engagement with the insulating body and the shell.

9. A spark plug of the character described and including a metallic shell, an insulating body, an inner non-ferrous metallic gasket having a cadmium plating, and means for maintaining the body and shell assembled and compressing the inner gasket into hermetic sealing engagement with the insulating body and the shell.

10. A spark plug of the character described and including a metallic shell, an insulating body, an inner non-ferrous metallic gasket having a tin-plating, and means for maintaining the body and shell assembled and compressing the inner gasket into hermetic sealing engagement with the insulating body and the shell.

11. A spark plug of the character described and comprising a metallic shell, an insulating body, an inner non-ferrous metallic gasket interposed between the metallic shell and the insulating body and having a soft metal surfacing capable of flowing into the pores of the insulating body when compressed between the body and the shell to effect a hermetic seal, and means for maintaining the body and shell assembled and also acting to compress the gasket into hermetic sealing engagement with the insulating body and the shell.

12. A spark plug of the character described and comprising a metallic shell, an insulating body, an inner non-ferrous metallic gasket having a

lead coating, and means for maintaining the body and shell assembled and compressing the inner gasket into hermetic sealing engagement with the insulating body and the shell.

5 13. A spark plug of the character described and comprising a metallic shell, an insulating body, an inner copper gasket interposed between the metallic shell and the insulating body and having

a soft metal coating capable of flowing into the pores of the insulating body when compressed between the body and the shell to effect an hermetic seal, and means for maintaining the body and the shell assembled and also acting to compress the gasket into hermetic sealing engagement with the insulating body and the shell. 5

CHARLES R. BUENING.
